UNITED STATES PATENT OFFICE.

CHARLES W. DAKE, OF GRAND RAPIDS, MICHIGAN, ASSIGNOR TO THE DAKE-AMERICAN STEAM TURBINE COMPANY, OF GRAND RAPIDS, MICHIGAN.

ELASTIC-FLUID TURBINE.

No. 903,454.

Specification of Letters Patent. Patented Nov. 10, 1908.

Application filed April 23, 1908. Serial No. 428,777.

To all whom it may concern:

Be it known that I, CHARLES W. DAKE, a citizen of the United States, residing at the city of Grand Rapids, county of Kent, State of Michigan, have invented certain new and useful Improvements in Elastic-Fluid Turbines, of which the following is a specification.

This invention relates to improvements in elastic fluid turbines.

The objects of my invention are: first, to increase the efficiency of elastic fluid turbines by a more effective form of the buckets in combination with the nozzle; second, to lessen the cost of construction both in the economizing of material and in lessening the labor cost of production; third, to provide a construction which is readily assembled and disassembled, and in which injured parts can be quickly substituted or repaired; and fourth, to improve the specific details of construction of the bucket.

Further objects will definitely appear from the detailed description to follow.

I accomplish the objects of my invention by the devices and means described in the following specification.

The invention is clearly defined and pointed out in the claims.

In the accompanying drawing I illustrate such parts of an elastic fluid turbine as are necessary to the proper understanding of my invention, in which:

Figure 1 is a sectional view transversely through the rim of a turbine, showing a detail of the rough blank in the first step of the process of manufacturing the buckets of my improved turbine, the view being taken on a plane indicated by the section lines Z—Z of Figs. 6 and 7. Fig. 2 is a similar sectional view showing the next step of the method of manufacture in which the annular groove for the buckets has been formed in the blank. Fig. 3 is a similar sectional view, showing the groove formed for receiving and seating the partition walls between the buckets. Fig. 4 is a detail elevation view of one of the said partition walls or plates. Fig. 5 is a detail sectional view similar to that appearing in Figs. 1, 2 and 3, except that the rim of the turbine is laid on its side, showing the partition walls in place in the rim. Fig. 6 is a detail view of a portion of the rim of a turbine and nozzle in position, being a side elevation looking squarely at the side into the

buckets. Fig. 7 is a detail sectional view of the structure as appearing in Fig. 6, taken on a plane corresponding to the curved line X—X of Fig. 6, looking in the direction of the little arrow. Fig. 8 shows a modified arrangement of the turbine wheel with the buckets on the periphery in place of on the face; and Fig. 9 is a cross section through the turbine nozzle 10.

In the drawing, similar numerals of reference refer to similar parts throughout the several views.

Considering the numbered parts of the drawing, a bucket segment or ring 1 is formed in the manner usual with my construction of elastic fluid turbine engine with a suitable shank with bolt hole therethrough for attachment to the central disk not here shown. In the face of this segment or ring, I cut a groove 2 which is in form one-half of an ellipse, the ellipse being divided on the long axis. This broad groove 2 is readily turned out after the turbine wheel has been assembled with the ring 1, either a full or segmental ring. After this has been done, I cut grooves 4 transversely across the annular bucket groove at an angle of about 20 degrees, by a suitable rotary cutter. The ellipse is of such form that when the cutter is set at an angle of 20 degrees it forms a true circle, so that the tool cuts an even groove out of the back wall. This tool, in cutting the metal, turns up a thin bur. After the groove is cut, I cut a notch 5, which is a continuation of the groove 4 out through the edge of the outer portion of the ring to receive a lug on the bucket partition wall.

The buckets are formed by inserting semi-circular pieces of sheet metal 7 with lugs 5' formed at the upper outer angle within the groove 4. When these semi-circular disks are punched from a sheet of metal, a bur 8 is raised around the edge of the same from the action of the punch, which bur I am careful to preserve on this sheet metal partition wall. It is utilized in the proper securing of the said partition wall within the bucket groove 2. The semi-circular partition wall 7 is inserted in the groove with the bur on the side towards the thin overhanging edge of the groove 4, and the lug 5' is brought into the notch 5. When this is done, a tool is passed over the thin upturned bur on the edge of the groove 4 and it is

bent by the rubbing action of a tool, somewhat like the spinning of metal, to engage the bur on the semi-circular partition plate 7, and this very effectively retains the said 5 partition in place. The lug 5' is then riveted down into the notch 5, when the partition wall is effectively and safely held in place. When this is done, the turbine wheel 10 is put into a lathe and the partition walls turned off to make them even, and a broad notch 7' is formed in the same towards the receiving end of the bucket, the discharge end of the bucket being indicated at 6. The position of this bucket partition 7 is clearly 15 indicated in Figs. 5 and 6.

A nozzle 10 with its end cut oblique is arranged in this broad notch 7 to deliver the elastic fluid most effectively into the buckets, and, as this construction enables very 20 thin partition walls to be placed between the buckets, the bucket capacity of a turbine is correspondingly increased and the angle of the nozzle and the position which it occupies, projecting into the notch, enables the 25 elastic fluid to be thus delivered most effectively. The result is a very marked increase in the efficiency of the entire engine.

In Fig. 8, I have shown how the buckets can be arranged on the periphery of a turbine wheel, in which event I prefer to form 30 lugs 5' on both sides of the bucket and retain them in suitable slots. From this description it will be seen that the bucket ring may be roughly formed to shape and turned true. The bucket groove 2 may then be formed therein by the use of a heavy tool, cutting the metal very rapidly. The partition walls can then be inserted by the action 35 of a light tool, forming a comparatively shallow groove to receive the thin sheet metal bucket partitions, which are made from punchings. The punchings should not be finished, because the bur is utilized as a part of the attaching means. This forms 40 the buckets very economically and very effectively, and by then shaping the buckets with the broad notch to receive the oblique-ended nozzle, the full bucket capacity and the most effective delivery of elastic fluid 45 is secured. Aside from economy in construction, greater efficiency in the elastic fluid turbine is thus secured.

The partitions 7 can be readily withdrawn and repaired or new ones inserted, a tool of 50 proper strength only being required.

Having thus described my invention, what I claim as new and desire to secure by Letters Patent is:

1. In an elastic fluid turbine, the combination 60 of the turbine wheel, with a bucket ring with an annular groove formed therein of semi-elliptical cross section on the long axis; semi-circular sheet metal bucket partitions inserted in transverse grooves in the bucket

groove and set at an angle thereto, the said 65 sheet metal partitions having a bur formed on their edge and being retained by compressing the bur on the edge of the said transverse groove against the same, the said partitions having a lug extending to one side 70 and riveted into a suitable notch, the said bucket partitions having a broad notch 7' in their free edges; and a nozzle with its end cut off obliquely to conform to the said notch, coacting substantially as described 75 and for the purpose specified.

2. In an elastic fluid turbine, the combination of the turbine wheel, with a bucket ring with an annular bucket groove formed therein semi-elliptical in cross section on 80 the long axis of the ellipse; substantially semi-circular sheet metal bucket partitions inserted at an angle in the said bucket groove and retained there by suitable means, a broad notch being formed in the free edge 85 of the said partitions; and a suitable nozzle with its end cut off oblique to conform to the said notch in said partitions, coacting substantially as described and for the purpose specified. 90

3. In an elastic fluid turbine, the combination of the turbine wheel with a bucket ring with an annular bucket groove formed therein; a sheet metal bucket partition arranged transverse to the said bucket groove in a 95 suitable notch in the wall thereof; a bur formed on the said sheet metal partition, engaged by a bur on the edge of the groove, being compressed against the same, coacting for the purpose specified. 100

4. In an elastic fluid turbine, the combination of the turbine wheel with a bucket ring with an annular bucket groove formed therein; a sheet metal bucket partition arranged transverse to the said bucket groove in a 105 suitable notch in the wall thereof; a bur formed on the said sheet metal partition, engaged by a bur on the edge of the groove, being compressed against the same, an extension or lug of the said partition being riveted into a notch in the wheel, coacting 110 for the purpose specified.

5. In an elastic fluid turbine, the combination of the turbine wheel with a bucket ring with an annular bucket groove formed therein; a sheet metal bucket partition arranged transverse to the said bucket groove in a 115 suitable notch in the wall thereof, an extension or lug of the said partition being riveted into a notch in the wheel, coacting for the purpose specified. 120

In witness whereof, I have hereunto set my hand and seal in the presence of two witnesses.
